1

This invention relates to an electrical switch of simple and durable construction, and highly reliable in operation.

One of the objects of the present invention is to provide an electrical switch having the desirable characteristics of rapidly closing and opening the circuit, thus avoiding bad connections and arcing at the contacts.

Another object is to provide a switch in which the contact bridge, when in the inoperative position, is positively incapable of accidentally establishing contact with the associated resilient contact members, owing to the fact that it is firmly maintained in a definite inoperative position, and in addition, the points of engagement between said contact members and the contact bridge are so arranged that electrical contact between them is impossible.

The new electrical switch includes two resilient conducting arms arranged in pincer fashion and adapted to retain in its operative position a movable bridging conductive member, represented by a ball, roller or the like, capable of passing from the operative to the inoperative position due to the thrust effect of means operated from the outside and under the resilient action of said electrical conducting means, the switch according to this invention being further characterized by the fact that the two conducting arms arranged in pincer fashion have curved portions intermediate of their length, adapted to cooperatively receive and retain the movable bridging member, one of the pincer arms being provided with an end extension that continues from the associated curved portion and is so shaped as to facilitate the release and the entrance of the bridging member, while the other resilient pincer arm has a bent resilient extension the free end of which is arranged at such a distance to the nearest part of the curved seating portion of the same arm, that the movable bridge is capable of moving from said curved portion to the free end without breaking contact with the conducting arm, an insulating shoe being mounted on the above mentioned free end of the bent resilient extension and which, when the contact bridge is in operative position, remains normally interposed between the conducting portions of the related arm and the other conducting arm, thus impeding the access of the contact bridge to the conductive pincer, said shoe having in addition a contact edge or face opposite to a corresponding portion of the other member, to form with said portion, a resilient impulsion couple which tends to force the contact bridge towards the inside of the pincer, during the operative stroke of said bridge.

Other objects and advantages of the invention will become apparent to those skilled in the art, from the following description taken in conjunc-

2

tion with the accompanying drawings illustrating a preferred embodiment of the invention and wherein:

Fig. 1 is an external perspective view of a single-pole wall switch.

Fig. 2 is another perspective but of a section of the same switch of Fig. 1, the contact bridge being in its operative position, between the arms of the pincer.

Fig. 3 is a lateral elevation and longitudinal section of the same switch, the contact bridge being shown still in its operative position between the arms of the pincer, but just about to be ejected from the arms of the pincer, in order to open the circuit.

Fig. 4 is similar to Fig. 3, but in which the movable contact bridge is in its inoperative position, and makes contact with only one of the conducting portions of the resilient arms of the pincer, so that the circuit in which the switch is interposed will remain open.

Fig. 5 is a perspective view of a three-pole switch, in which, to simplify the drawing, some parts have been eliminated, for instance the cover and the main base.

Fig. 6 is a side elevation and sectional view of a switch of the type of Fig. 5, but without eliminating the above mentioned parts.

The same reference characters are used to indicate like or corresponding parts or elements throughout the drawings.

In accordance with that illustrated in Figs. 1 to 4, corresponding to a single-pole switch, *a* is an external box in the shape of a prism having irregular hexagonal bases which are indicated with the numerals 1, 1'. One of the side faces is removable for access to the interior of the switch, while the largest side 2 constitutes the front of the box. When the box is embedded in the cavity of a wall, the sides 3 and 7 of the same box form respectively the upper and lower base. The remaining sides, 4, 5 and 6 form the back wall of the box. The holes 8, formed in the front 2 and walls 4 and 6, are used for attaching the box, and consequently the switch, to the corresponding wall cavity, in which the usual metal fittings must be provided for the mounting screws adapted to grip the box *a* through the holes 8.

The construction of the outer box *a* is completed with a rectangular window 9, formed in the front wall 2 and adapted, as will be shown later, to receive the operating handle of the switch.

Within the box *a* is provided a movable body *b* generally shaped as a prism of hexagonal base, similar to *a*, but smaller and without the bases that would correspond to the surfaces 1 and 1' of the box *a*. As may be seen in Figs 2 to 4, the inner movable body *b*, which has a front 10, two bases 11 and 12 and three rear faces 13, 14 and

15, is loosely fitted between the front 2 and the rear wall 5 of the box *a*, said front and rear walls acting as longitudinal guides for the movements of body *b*. This movable body *b* is of appreciably less height than the box *a*, so that it may be displaced within the box by means of the handle 16 projecting out of the box *a* through the window 9. It should be understood that the window 9 must preferably be of such dimensions as to provide only sufficient space for the passage and necessary movement of said handle, thus serving as a guide and movement limiting means for said handle. Thus, it will be also observed that the outer box *a* being only opened at its window portion 9, and the front 10 being applied directly against the inner face 2 of the box *a*, the interior of the switch, and consequently all the inside elements will be protected from dust.

The side wall 1' of the box *a* is provided with two interiorly projecting supports 17 and 18 which are disposed within the movable body *b*. On these supports there are fixed by means of the corresponding screws 19 the resilient arms *c* and *d* arranged face to face, as shown in Figs. 2, 3, and 4. The conducting wires *e* may also be affixed to these screws. The two resilient arms are made of metal sheet having a high electrical conductivity and are shaped according to the interrupted sinusoidal form as illustrated, both having curved intermediate portions 20 and 21, so dimensioned as to form cooperating retaining seats for the movable bridging member *f*, also made of conducting material. This member is represented as a cylinder, although it will be apparent that it may be in the form of a spherical ball or any other body having a suitably curved surface. The movable member *f* has as lateral guides the walls 1 and 1' of the box *a*, spaced apart at a distance slightly greater than the length of said member.

The two above mentioned resilient arms, due to their constructive and operational characteristics, constitute a form of retaining pincer for the bridging member *f*. Beyond its curved seat portion 21, the arm *d* is provided with a slightly curved short extension 22, adapted to serve as a point for the ejection or entrance of the roller constituting the movable contact bridge.

Referring now to the resilient arm *c* this is also provided with an extension formed beyond the intermediate seat portion 20. Unlike the arm *d*, the end extension 23 of the arm *c* is bent in the form of a U, the two legs of which face towards the other resilient arm. The leg 23', which is the farthest spaced from the intermediate curved seat 20 is located at such a distance from such seat that the roller *f* when being displaced towards said leg 23' engages said leg before leaving its seat, whereby the continuity of connection between the two arms is not interrupted. The leg 23' is so proportioned and disposed that its free end, which may be provided with a slightly widened portion 23'' in order to offer a greater contact surface to the roller *f*, faces the extension 22 of the arm *d*, and is spaced at such a distance from the extension 22 of the arm *d* that the roller *f* is gripped in a pincer-like fashion when moving from the extreme operative position of Fig. 2 to the intermediate position of Fig. 3.

In the free leg 23' of the U-shaped bend 23 which also includes the slightly widened portion 23'', there is loosely mounted an insulating shoe *g*, which has an arm 24 terminating in a bend 24', which, as shown in Fig. 2, cooperates with the leg of the U-shaped bend located immediately beyond the seat 20 of the arm *c*. In this way, the

bend 24' partially surrounds the aforementioned leg of the arm *c* in order to limit indirectly the movements of the other previously mentioned leg 23'. This ensures that the leg 23' will be always maintained at a minimum distance from the seat 20, thus providing for the electrical continuity of the connection between the arms *c* and *d* when the roller *f* moves away from the seats 20 and 21. A part of the contour of the shoe *g* is curve shaped similarly to the outer surface of the roller *f*, so that it fits firmly over said roller, as shown in Fig. 4. Between the portion 25 and the leg 23' of the bend 23 is a short straight portion 26, against which the roller *f* bears initially when being inserted between the arms *c* and *d* of the conducting pincers so that the roller is held between the non-conducting portion 26 of the shoe and the end extension 22 of arm *d*, which, due to its spring tension is capable of snapping the conducting roller into the pincers at the appropriate time.

It will be seen from Figs. 2, 3 and 4, that the switch, as described, is provided with two stops 27 integral with the side wall 1' of box *a* and adapted to maintain the roller *f* in its inoperative position, and limiting its spacing from the seats 20 and 21 of the pincers (Fig. 4). There are also provided two other stops 28 and 28' which are movable and serve as means for moving the roller member employed as the connecting bridge element of the switch. These two stops 28 and 28' are formed in or fitted in line with but opposite each other on the interior walls of the inside movable body having been arranged oppositely and on the same line at the side walls *b* and are positioned so as to engage the bridging roller at two diametrically opposed points, and to pass between the arms of the conducting pincers when moved to and from the extreme positions illustrated in Figs. 2 and 4 respectively.

From the foregoing, it will be seen that in the embodiment illustrated by Figs. 1 to 4, the movable contact bridge represented by the hollow metal roller, is subject at all times to the action of the conducting arms *c* and *d*, arranged in pincer like fashion. The arms do not however, act by themselves, but their action is assisted by the movable stops 28 and 28', which in turn are actuated externally at will by means of the handle 16.

The effect, the movable stops 28 and 28' represent the means, controlled by the user of the switch, by which movement of the contact bridge is initiated in order to place it in the operative or the inoperative position. These stops, however, are not capable of controlling the moving bridge in the last stage of its displacement, which takes place under the action of the arms *c* and *d* of the spring pincers and which are completely outside the control of the operator. This detail is of the utmost importance, since it ensures the completion of the final part of the displacement of the bridging roller, independently of the operator of the switch, who is therefore prevented from incorrectly operating the bridge and thus causing, either deliberately or accidentally, false contacts when the bridge is introduced or withdrawn from between the arms of the pincers.

Thus, when the bridge *f* is in the operative position as shown in Fig. 2 in which it is gripped between the two cooperating seats 20 and 21 of the arms *c* and *d* for closing the electric circuit of the switch, it is necessary, in order to move the bridge to the inoperative open circuit position as shown in Fig. 4, to cause the internal

movable body *b* to move downwards by moving the handle *16* in the same direction. The movable stop *28* then advances towards the bridge *f* and the stop *28'* moves away from it as the other stop advances. As the bridge moves away from the seats *20* and *21*, the arms *c* and *d* of the resilient pincers open sufficiently to allow of the passage of the bridging roller. During its movement, the latter roller reaches the position shown in Fig. 3, in which position it has practically left the seats in which it was retained, and is actually tightly pressed by the two arms of the pincer; and is just about to be ejected at an even greater distance from said seats. It should be noted that in said intermediate position in which the bridge is still engaging the arms of the pincer, the roller *f* is also engaging the free end *23'* of the U extension of the arm *c*; i. e., it maintains a double contact with said arm. This is important since, as the ejection of the roller to the inoperative position of Fig. 4 must occur under the pressure of the free end of the bend *23* and the opposite angular portion of the other arm of the pincer, it is necessary that until said ejection is effected the roller is maintained in contact with both arms of the pincer. If, in passing from its position between the seats *20* and *21* to the position in which it engages the free end of the bend *23*, the roller *f* were to become momentarily disengaged from the arm *c* (at this stage of its movement, the roller is controllable from outside), it would be possible to produce a slow breaking of the contact between both parts, with the consequent detrimental results.

As soon as the movable stop *28* advances a little farther, the two parts of the resilient pincer that press firmly on the curved surface of the roller, begin to slip along said surface, in a natural and independent closing movement, due to spring action, and by "pinching" the roller, sharply eject it against the stops *27*. This breaks the contact between *c* and *d*, and leaves the roller firmly held against the stops *27*, on account of the fact that the arms of the pincer continue their movement and close behind the roller. The latter is thus retained between the stops *27*, the shoe *g* and the end extension *22* of the arm *d*, as shown in Fig. 4. The movable stop *28*, however, is made of such a length that it does not advance beyond the position reached when the two arms of the resilient pincer start the "pinching" action on the roller.

To reclose the circuit, by restoring the bridging roller to the initial position as shown in Fig. 2, the handle *16* is operated in the reverse direction to raise the inner movable body. Thus the movable stop *28'* approaches the contact roller, and the stop *28* moves away from it. When the stop *28'* engages the roller *f* and commences to force it between the contact pincers, the arms *c* and *d* of said pincer open but maintain contact with the roller, on account of their elasticity. At the initial stage of the movement of the roller, it engages the conducting position *22* of the arm *d* and the non-conducting shoe of the arm *c*, and thus the two arms are not electrically connected. In yielding to the action of the roller, the shoe moves to the left until its rectilinear contour portion *26* is applied against the curved surface of the roller and the diametrically opposed part of the roller is engaged by a portion of the arm *d* corresponding to its end extension *22* or to the ridge separating said part from the seat *21*. Although the roller makes contact with the portion *26* of the shoe *g*, it does not enter into contact

with the free end of the branch *23'* of the bend *23* of the arm *c*. In continuing the movement of the stop *28'*, when the roller *f* is in a position very similar, although not equal, to that shown in Fig. 3, said roller, without engaging at any moment the free end of the branch *23'*, is sharply ejected, also by a "pinching" action of the two pincer arms, towards the seats *20* and *21* of said pincer, thus producing electrical contact between the two arms, and the resulting closing of the circuit. The resilient arms of the pincer follow the movement of the roller and are instantaneously applied at both sides of the roller, the whole assembly assuming the position shown in Fig. 2.

The three-pole switch of Figs. 5 and 6 is essentially a multiplication of the above described single pole switch. The three pairs of resilient arms *c'* with shoes *g'* and *d'* are substantially similar to the corresponding elements *c* and *d* of the other switch and operate in like manner and similar conductor rollers *f'* are also used. The arms *c'* and *d'* are firmly attached by means of screws *29* against the inner face of the vertical plate *30*. This plate is in turn attached to the intermediate base plate *31*, which is maintained in a raised position over the principal base *32*, by means of the bolts *33*. For the external operation of the rollers *f'* there is provided a sliding member *h* made of insulating material and comprising, as may be seen in Fig. 5, a plate *34* with an internal opening *35* which allows of the formation of the movable stops *36* and *36'* adapted to move the respective rollers, and of the large recesses *37* adapted to operate as guides for the plate *34* itself and as means for limiting its displacement. The small vertical stop and guide partitions *38* cooperate with the sliding member *h* and are adapted to assist in the guiding of the sliding member *h*, to limit the extent of the movement of said member, and to maintain the bridging rollers *f'* in their lateral position. The sliding member *h* is provided with a handle *39* attached at its fore end and is arranged horizontally between the arms of the cooperating resilient conducting pincers, being maintained in correct position and free for longitudinal movement by means of two lateral guiding supports *40* attached with screws *41* to the base plate *31*.

The conducting wires *e'* are connected directly to the terminals *29'* (Fig. 6) formed by nuts threaded on to the ends of the screws *29* which are used to attach the arms *c'* and *d'* to the support *30*.

The operation of the three pole switch is substantially similar to the operation of the single pole switch previously described with reference to Figs. 1 to 4, as all the essential elements are practically the same. Thus, when the sliding member *h* is moved by pulling the handle *29*, the movable stops *36* simultaneously start to move the rollers *f'* away from the seats of the resilient pincers. Each of the rollers is then swiftly ejected in the manner described, above, and remain gripped in the inoperative position (open circuit), between the cooperating stop *36*, the conducting end of the arm *d'* and the insulating shoe *g'*. By moving the insulating sliding member *h* in the reverse direction, the rollers may be replaced as in the case of the single pole switch to their operative closed circuit positions. In this way, it is possible to obtain a sure and simultaneous opening or closing of the circuit in each one of the three pincer units of the switch.

It will be clear that in carrying the present invention into practice, modifications may be

made as regards certain details of the construction of the electrical switch described, but always provided that such modifications do not depart from the fundamental principles which are clearly set forth in the accompanying claims.

We claim:

1. An electrical switch including two resilient conductive arms arranged in pincer like fashion and adapted to retain in its operative position a movable conductive bridging member represented by a roller, ball or the like capable of passing from the operative to the inoperative position or vice versa by a thrust action of externally actuated means and by the resilient effect of said electrically conductive arms, wherein the two conductive arms arranged in pincer like fashion are provided at their respective intermediate portions with oppositely curved seating sections, adapted to cooperatively receive and retain the movable bridging member, one of the pincer arms having an end extension that continues from the associated curved portion and is so shaped as to facilitate the release and the entrance of the bridging member, while the other resilient pincer arm has a bent resilient extension the free end of which is arranged at such a distance from the nearest part of the curved seating portion of the same arm, that the movable bridge is capable of moving from said curved portion to the free end without breaking its contact with the conductive arm, an insulating shoe being mounted on the above mentioned free end of the resilient bent extension and which, when the contact bridge is in operative position, remains normally interposed between the conducting portions of the related arm and the other conductive arm, thus blocking the access of the contact bridge to the conductive pincer, said shoe having in addition a contact zone facing an associated portion of the other member, to form with said portion a resilient pair for impulsion of the contact bridge towards the inside of the pincer, during the operative stroke of said bridge.

2. An electrical switch including two resilient conductive arms arranged in pincer like fashion and adapted to retain in its operative position a movable conductive bridging member represented by a roller, ball or the like capable of passing from the operative to the inoperative position or vice versa by a thrust action effected by externally actuated means and by the resilient effect of said electrically conductive arms, wherein the two conductive arms arranged in pincer like fashion are provided at their respective intermediate portions with oppositely curved seating sections, adapted to cooperatively receive and retain the movable bridging member, one of the pincer arms having an end extension that continues from the associated curved section and is so shaped as to facilitate the release and the entrance of the bridging member, while the other resilient pincer arm has an extension bent in the form of a U with the legs of the U looking facing towards the first pincer arm and with the free end of the extension arranged at such a distance from the nearest part of the curved seating section of the same arm, that the movable bridge is capable of moving past said curved section of the free end without breaking contact with the conductive arm, an insulating shoe being mounted on the above mentioned free end of the resilient U shaped extension which, when the contact bridge is in its operative position, remains normally interposed between the conducting portions of the related arm and the other conduct-

ing arm, thus blocking the access of the contact bridge to the conductive pincer, said shoe having in addition a contact zone facing an associated portion of the other member, to form with said portion a resilient pair for the impulsion of the contact bridge towards the inside of the pincer, during the operative stroke of said bridge.

3. An electrical switch including two resilient conductive arms arranged in pincer like fashion and adapted to retain in its operative position a movable conductive bridging member represented by a roller, ball or the like capable of passing from the operative to the inoperative position or vice versa by the thrust action of externally actuated means and by the resilient effect of said electrically conductive arms, wherein the two conductive arms arranged in pincer like fashion are provided at their respective intermediate portions with oppositely curved seating portions, adapted to cooperatively receive and retain the movable bridging member, one of the pincer arms having an end extension that continues from the associated curved portion and is so shaped as to facilitate the release and the entrance of the bridging member, while the other resilient pincer arm has a bent resilient extension, the free end of which is arranged at such a distance from the nearest part of the curved seating portion of the same arm that the movable bridge is capable of moving past said curved portion of the free end without breaking contact with the conductive arm, an insulating shoe being mounted on the above mentioned free end of the resilient bent extension which when the contact bridge is in its operative position, remains normally interposed between the conducting portions of the related arm and the other conductive arm, thus blocking the access of the contact bridge to the conductive pincer, said shoe having a curved portion adapted to engage the curved surface of the contact bridge, a small, preferably straight, portion being disposed adjacent to said curved portion to form the contact zone and adapted to engage said contact bridge only during the movement of said bridge from the inoperative to the operative position in order to form the resilient pair for the operative impulsion of said bridge.

4. An electrical switch including two resilient conductive arms arranged in pincer like fashion and adapted to retain in its operative position a movable conductive bridging member represented by a roller, ball or the like capable of passing from the operative to the inoperative position or vice versa by the thrust action of externally actuated means and by the resilient effect of said electrically conductive arms, wherein the two conductive arms arranged in pincer like fashion are provided at their respective intermediate portions with oppositely curved seating portions, adapted to cooperatively receive and retain the movable bridging member, one of the pincer arms having an end extension that continues from the associated curved portion and is so shaped as to facilitate the release and entrance of the bridging member, while the other resilient pincer arm has a bent resilient extension, the free end of which is arranged at such a distance from the nearest part of the curved seating portion of the same arm, that the movable bridge is capable of moving past said curved portion of the free end without breaking its contact with the conductive arm, an insulating shoe being fixedly attached to the branch of the bent portion of the corresponding resilient arm which is more remote from the curved seating portion, and provided with an arm

engaging the other branch of the bent portion for limiting the spacing between said two branches, said shoe being adapted when the contact bridge is in its operative position to remain normally interposed between the conductive portions of the related arm and the other conductive arm, and having in addition a contact zone facing an associated portion of the other member, to form with said portion a resilient pair for the impulsion of the contact bridge towards the inside of the pincer, during the operative stroke of said bridge.

5. An electrical switch including two resilient conductive arms arranged in pincer like fashion and adapted to retain in its operative position a movable conductive bridging member represented by a roller, ball or the like capable of passing from the operative to the inoperative position or vice versa by the thrust action of externally actuated means and by the resilient effect of said electrically conductive arms, wherein the two conductive arms arranged in pincer like fashion are provided at their respective intermediate portions with oppositely curved seating portions, adapted to cooperatively receive and retain the movable bridging member, one of the pincer arms having an end extension that continues from the associated curved portion and is so shaped as to facilitate the release and entrance of the bridging member, while the other resilient pincer arm has a bent resilient extension the free end of which is arranged at such a distance from the nearest part of the curved seating portion of the same arm, that the movable bridge is capable of moving past said curved portion of the free end without breaking its contact with the conductive arm, an insulated shoe being mounted on the above mentioned free end of the resilient bent extension which when the contact bridge is in the operative position, remains normally interposed between the conducting portions of the related arm and the other conductive arm thus blocking the access of the contact bridge to the conductive pincer, said shoe having in addition a contact zone slightly more protruding than the most advanced portion of the free end of the conductive bent portion of said pincer arm and facing an associated portion of the other member, to form with said portion a resilient pair for the impulsion of the contact bridge towards the inside of the pincer during the operative stroke of said bridge.

6. An electrical switch including two resilient conductive arms arranged in pincer like fashion and adapted to retain in its operative position a movable conductive bridging member represented by a roller, ball or the like, said conductive resilient arms being fixed to one of the side walls of an external box having a second side wall substantially parallel to the first mentioned side wall to guide the movable contact bridge and to guide an internal sliding body having movable stops adapted to move said movable bridge in cooperation with the resilient action of said electrically conductive arms either to the operative or to the inoperative position of said body, wherein the two conductive arms arranged in pincer like fashion are provided at their respective intermediate portions with oppositely curved seating sections, adapted to cooperatively receive and retain the movable bridging member, one of the pincer arms having an end extension that continues from the associated curved portion and is so shaped as to facilitate the release and the entrance of the bridging member, while the other

resilient pincer arm has a bent resilient extension the free end of which is arranged at such a distance from the nearest part of the curved seating portion of the same arm, that the movable bridge is capable of moving from said curved portion to the free end without breaking its contact with the conductive arm, an insulated shoe being mounted on the above mentioned free end of the resilient bent extension and which, when the contact bridge is in operative position, remains normally interposed between the conducting portions of the related arm and the other conductive arm, thus blocking the access of the contact bridge to the conductive pincer, said shoe having in addition a contact zone facing an associated portion of the other member, to form with said portion a resilient pair for impulsion of the contact bridge towards the inside of the pincer, during the operative stroke of said bridge.

7. An electrical switch including two resilient conductive arms arranged in pincer like fashion and adapted to retain in its operative position a movable conductive bridging member represented by a roller, ball or the like capable of passing from the operative to the inoperative position or vice versa, said conductive resilient arms being fixed to one of the side walls of an external box shaped as an orthogonal prism having polygonal bases with said bases constituting the sides 30 of the box and one of the side walls forming the front of the box, an opening in the front wall adapted to accommodate, and serve as a guide means, for the operating handle of the switch, said handle being fixed to the front wall of an internal sliding body having movable stops adapted to move said movable bridge, in cooperation with the resilient action of said electrically conductive arms, either to the operative or to the inoperative position of said body, and said front wall of said internal sliding body being slidably applied against the inner face of the front wall of the external box, wherein the two conductive arms arranged in pincer like fashion are provided at their respective intermediate portions with oppositely curved seating sections, adapted to cooperatively receive and retain the movable bridging member, one of the pincer arms having an end extension that continues from the associated curved portion and is so shaped as to facilitate the release and the entrance of the bridging member, while the other resilient pincer arm has a bent resilient extension the free end of which is arranged at such a distance from the nearest part of the curved seating portion of the same arm, that the movable bridge is capable of moving from said curved portion to the free end without breaking its contact with the conductive arm, an insulated shoe being mounted on the above mentioned free end of the resilient bent extension and which, when the contact bridge is in operative position, remains normally interposed between the conducting portions of the related arm and the other conductive arm, thus blocking the access of the contact bridge to the conductive pincer, said shoe having in addition a contact zone facing an associated portion of the other member, to form with said portion a resilient pair for impulsion of the contact bridge towards the inside of the pincer, during the operative stroke of said bridge.

8. In an electrical switch, a plurality of electrical switching units, each unit including two resilient conductive arms arranged in pincer like fashion and adapted to retain in its operative position a movable conductive bridging member

represented by a roller, ball or the like capable of passing from the operative to the inoperative position or vice versa by the thrust action of opposing projections formed in the cut out portion of a sliding plate adapted to be displaced relatively to said bridges, said cut out portion being provided with pairs of respectively opposed notches adapted to cooperate with small guiding partitions located at the sides of and adapted to guide the respective bridges, wherein the two conductive arms arranged in pincer like fashion of each switching unit are provided at their respective intermediate portions with oppositely curved seating portions, adapted to cooperatively receive and retain the related movable bridging member, one of the pincer arms of each unit having an end extension that continues from the associated curved portion and is so shaped as to facilitate the release and entrance of the bridging member, while the other resilient pincer arm of the same unit has a bent resilient extension the free end of which is arranged at such a distance from the nearest part of the curved seating portion of the same arm, that the movable bridge is capable of moving past said curved portion of the free end without breaking its contact with the conductive arm, an insulating shoe being mounted on the above mentioned free end of the resilient bent extension which when the contact bridge is in its operative position, remains normally interposed between the conducting portions of the related arm and the other conductive arm, thus blocking the access of the contact bridge to the conductive pincer, said shoe having in addition a contact zone facing an associated portion of the other member, to form with said portion a resilient pair for the impulsion of the contact bridge towards the inside of the pincer, during the operative stroke of said bridge.

9. In an electrical switch, a plurality of electrical switching units, each unit including two resilient conductive arms arranged in pincer like fashion and adapted to retain in its operative position a movable conductive bridging member represented by a roller, ball or the like capable of passing from the operative to the inoperative position or vice versa by the thrust action of opposing projections formed in the cut out portion of a sliding plate adapted to be displaced relatively to said bridges, said cut out portion being provided with pairs of respectively opposed notches adapted to cooperate with small guiding partitions located at the sides of and adapted to guide the respective bridges, wherein the two conductive arms arranged in pincer like fashion of each switching unit are provided at their respective intermediate portions with oppositely curved seating portions, adapted to cooperatively receive and retain the related movable bridging member, one of the pincer arms of each unit having an end extension that continues from the associated curved portion and is so shaped as to facilitate the release and entrance of the bridging member, while the other resilient pincer arm of the same unit has a bent resilient extension the free end of which is arranged at such a distance from the nearest part of the curved seating portion of the same arm, that the movable bridge is capable of moving past said curved portion of the free end without breaking its contact with the conductive arm, an insulating shoe being mounted on the above mentioned free end of the resilient bent extension which when

the contact bridge is in its operative position, remains normally interposed between the conducting portions of the related arm and the other conductive arm, thus blocking the access of the contact bridge to the conductive pincer, said shoe having in addition a contact zone facing an associated portion of the other member, to form with said portion a resilient pair for the impulsion of the contact bridge towards the inside of the pincer, during the operative stroke of said bridge, said sliding plate being slidably mounted in parallel relationship with an intermediate base plate which in turn is fixedly mounted at a distance from a main base plate, the pincer arms being firmly attached to a vertical partition.

10. In an electrical switch, a plurality of electrical switching units, each unit including two resilient conductive arms arranged in pincer like fashion and adapted to retain in its operative position a movable conductive bridging member represented by a roller, ball or the like capable of passing from the operative to the inoperative position or vice versa by the thrust action of opposing projections formed in the cut out portion of a sliding plate adapted to be displaced relatively to said bridges, said cut out portion being provided with pairs of respectively opposed notches adapted to cooperate with small guiding partitions located at the sides of and adapted to guide the respective bridges, wherein the two conductive arms arranged in pincer like fashion of each switching unit are provided at their respective intermediate portions with oppositely curved seating portions, adapted to cooperatively receive and retain the related movable bridging member, one of the pincer arms of each unit having an end extension that continues from the associated curved portion and is so shaped as to facilitate the release and entrance of the bridging member, while the other resilient pincer arm of the same unit has a bent resilient extension the free end of which is arranged at such a distance from the nearest part of the curved seating portion of the same arm, that the movable bridge is capable of moving past said curved portion of the free end without breaking its contact with the conductive arm, an insulating shoe being mounted on the above mentioned free end of the resilient bent extension which when the contact bridge is in its operative position, remains normally interposed between the conducting portions of the related arm and the other conductive arm, thus blocking the access of the contact bridge to the conductive pincer, said shoe having in addition a contact zone facing an associated portion of the other member, to form with said portion a resilient pair for the impulsion of the contact bridge towards the inside of the pincer, during the operative stroke of said bridge, said sliding plate being slidably mounted in parallel relationship with an intermediate base plate which in turn is fixedly mounted at a distance from a main base plate, the pincer arms being firmly attached to a vertical partition, and a cover being provided to protect the essential elements of the switch, fitted over the main base plate and provided with an aperture in its front for the passage of a handle adapted to operate the sliding plate from the outside of said box.
